US00D691088S

(12) **United States Design Patent**
Helosvuori et al.

(10) **Patent No.:** **US D691,088 S**
(45) **Date of Patent:** **** Oct. 8, 2013**

(54) **EQUIPMENT FOR DISTRIBUTION OF ELECTRIC POWER**

(71) Applicants: **Juhani Helosvuori**, Riihimäki (FI); **Marjukka Makela**, Helsinki (FI)

(72) Inventors: **Juhani Helosvuori**, Riihimäki (FI); **Marjukka Makela**, Helsinki (FI)

(73) Assignee: **ABB Oy**, Helsinki (FI)

(**) Term: **14 Years**

(21) Appl. No.: **29/449,093**

(22) Filed: **Mar. 14, 2013**

Related U.S. Application Data

(62) Division of application No. 29/371,782, filed on Sep. 22, 2011, now Pat. No. Des. 686,158.

(57) **CLAIM**

The ornamental design for an equipment for distribution of electric power, as shown and described.

DESCRIPTION

FIG. 1 is a perspective top, front and left side view of an equipment for distribution of electric power showing our new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof; and,

FIG. 8 is a perspective top, front and right side view thereof. The broken line portion of the figure drawings is included to show unclaimed subject matter only and forms no part of the claimed design.

1 Claim, 8 Drawing Sheets
